UNITED STATES PATENT OFFICE.

DEXTER W. LILES, OF BADIN, NORTH CAROLINA.

BOTTLE OPENER.

Application filed August 13, 1925. Serial No. 50,071.

This invention relates to bottle openers and more particularly to bottle cap or crown seal removers.

The object of the invention is to provide a simple and efficient opener constructed so as to eliminate the possibility of breaking the bottle or chipping its mouth during the removal of the crown.

Another object is to provide a device of this character equipped with means to forcibly engage the center of a crown and cause it to buckle inside the bottle neck thereby releasing the flange of the crown from outside the bottle neck.

With the foregoing and other objects in view which will appear as the description proceeds the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:—

Figure 1 represents a longitudinal section of the opener shown applied, the bottle being in side elevation.

Figure 2 is a front elevation of the opener detached; and

Figure 3 is a bottom plan view thereof;

Figure 4 is a front elevation of another form of the invention;

Figure 5 is a side view thereof;

Figure 6 is a longitudinal section taken on the line 6—6 of Figure 4.

The opener 10 constituting this invention shown in Figures 1 to 3 is designed to be mounted on a wall W or other suitable support, the bottle to be opened being shown at 1 and the crown seal constituting the closure therefor at 2.

The opener is preferably made of cast metal of the shape shown in the drawing having a flat front face or top 11 with an opening 12 therein on the rear wall 13 of which is formed an integral crown engaging member 14 which tapers from its lower toward its upper end as shown at 15 providing a projection 16 at its lower end which is designed to engage the center of the crown seal 2 during the opening operation.

The rear face of the opener is arranged at an acute angle to the front face 11 as shown

at 17 and is designed to rest against the wall W and to be secured thereto by screws passing through openings 18.

The lower wall of the opening 12 is curved on its inner face as shown at 19 the curvature thereof conforming to the shape of the bottle neck in connection with which it is to be used. The upper face of this wall is also curved and is equipped with a knife edge 20 designed to engage under the flange 3 of cap 2 so that when a downward pull is exerted on the bottle 1 the projection 14 will bear against the cap over the opening in the bottle mouth buckling the cap into the bottle neck and releasing it from the bottle without danger of breakage.

In Figures 3 to 6 another form of the invention is illustrated in which the opener is cut out of a sheet of steel in the form of a hood with the laterally extending wings 21 and 22 arranged at the rear upper portion thereof and which are apertured to receive fastening screws for attaching the device to a suitable support.

The top portion of the hood 10^a is made flat and the front thereof has an opening 23 struck out therefrom with a tongue 24 formed along the rear edge of said opening and bent downwardly with its free end extended forwardly and tapered to form a crown engaging projection 25. The front edge of the opening 23 is sharpened as shown at 26 and is designed to engage under the edge of the bottle cap, in the same manner as that shown in Fig. 1, so that when a pull is exerted on the bottle the projection 25 will bear against the center of the cap and force it inward while the sharp edge 26 under the flange will force the cap off the bottle mouth without any breaking of the glass.

It will thus be seen that this sheet metal form may be easily struck out and cheaply made so that it may be sold for a nominal price, and thus be within the reach of everybody.

I claim:—

In a bottle opener, a body portion including a length of sheet metal bent to provide lateral side members, ears formed on the lateral side members, said ears having openings to receive securing screws to secure the device to a supporting structure, said body portion having an opening stamped

therein, one edge of the opening being formed into a knife-like edge, a depending tongue having a forwardly extended end portion extending from one wall of the opening, said knife-like edge adapted to engage one edge of a bottle cap, and said forwardly extended end portion adapted to

engage the outer surface of the bottle cap to bend the same at this point.

In testimony that I claim the foregoing 10 as my own, I have hereto affixed my signature.

DEXTER W. LILES.
